BASE KETTLE FOR A MUSICAL DRUM

Robert L. Leighton, Box 22, Cortez, Colo. 81321

Filed Mar. 5, 1971, Ser. No. 121,613

Term of patent 14 years

Int. Cl. D17—04

U.S. Cl. D56—1 E

— 1 —

FIG. 2

FIG. 1

FIG. 4

FIG. 1 is a front elevational view of a base kettle for a musical drum, showing my new design;

FIG. 2 is a rear elevational view;

FIG. 3 is a top plan view; and

FIG. 4 is a bottom plan view thereof.

The kettle is symmetrical except for the legs and the thickness is substantially the same throughout.

I claim:

The ornamental design for a base kettle for a musical drum, as shown and described.
